COMBUSTION APPARATUS

John W. Miller and Vaughn H. Hill, Lansing,
Mich., assignors to Motor Wheel Corporation,
Lansing, Mich., a corporation of Michigan

Application October 14, 1939, Serial No. 299,471

2 Claims. (Cl. 158—91)

This invention relates to burners of the vaporizing pot type.

The principal object of this invention is the provision of means for improving the operation of such burners in their lower stages of operation without interfering with the desired and characteristic high fire operation. This object is attained by providing the burner with baffle means of novel construction and arrangement within the burner. The baffle means comprises a plurality of arcuate sections constituting segments of a centrally apertured disk arranged with alternate sections spaced vertically. By this means the lower part of the burner is separated from the upper part and is itself divided into a plurality of zones of varying size, with one of the smaller zones including the fuel inlet opening.

The preferred embodiment of the invention is illustrated in the accompanying drawing, wherein:

Figure 1 is a vertical sectional view of a space heater including a burner of the vaporizing pot type, the burner section being taken on substantially the line 1—1 of Figure 2;

Figure 2 is a horizontal section taken on substantially the line 2—2 of Figure 1; and

Figure 3 is a vertical section of the burner taken on substantially the line 3—3 of Figure 2.

The space heater shown in Figure 1 includes a cylindrical casing 10 closed at its upper extremity by a top wall 11 and supported at its lower extremity by a pair of crossed supporting straps 12 and 13 which are formed at their opposite extremities to provide legs 14.

The upper portion of the casing 10 forms a combustion chamber 15 and the lower portion forms an air compartment 16 adapted to receive a burner 17. The present invention resides in the burner 17 and it will be described in detail presently.

Access is had to the combustion chamber 15 through a door 18 in the front thereof. The door 18 also serves to provide means for introducing a lighted taper into the apparatus to initially ignite the oil. The products of combustion are withdrawn from the combustion chamber 15 through a flue outlet 19 having one end associated with the upper portion of the combustion chamber 15 and its other end communicating with a chimney 20. The flue outlet 19 is preferably provided, as shown, with an automatic draft regulator 21 whereby to maintain a constant draft on the apparatus. It will of course be apparent that the air compartment 16, in which the burner 17 is located, is open to

the atmosphere by reason of the construction of the supporting straps 12 and 13 previously mentioned.

The burner 17 includes a bottom wall 22, a side wall 23, a top wall 24, an anti-explosion baffle 25, and baffle means 26 disposed within the burner. The top wall 24 is provided with a large central opening 24a. The side wall 23 of the burner 17 is formed adjacent its upper extremity to provide a radially outwardly extending annular rib 28 and a radially inwardly extending annular rib 29 therebelow. The top wall is supported upon the radially inwardly extending annular rib 29. The anti-explosion baffle 25 is positioned above and supported by the top wall 24.

The baffle means 26 is made up of four arcuate sections A, B, C and D constituting segments of a centrally apertured disk. Adjacent ends of adjacent sections are joined to each other by vertical walls E of a radial width equal to the radial extent of the sections.

Air is admitted to the apparatus through primary air inlet openings 30 and secondary air inlet openings 31. The primary air inlet openings are formed in the side wall 23 below the top wall and are arranged in vertically spaced horizontal rows, the openings in each row being spaced circumferentially. The secondary air inlet openings are formed in the side wall 23 above the top wall 24 and below the anti-explosion baffle 25. They are located in the lower leg of the radially outwardly extending annular rib 28 whereby the air admitted therethrough is directed inwardly and upwardly. The anti-explosion baffle 25 and the secondary air inlet openings 31 are constructed and arranged with the axis of the openings intersecting the horizontal plane of the baffle whereby the air admitted through the secondary air inlet openings impinges against the baffle.

All of the air inlet openings 30 and 31 are in communication with the lower part of the casing forming the air compartment 16 and through it with the atmosphere. Consequently, both the primary and secondary air is drawn into the apparatus by means of the draft communicated to the apparatus from the chimney.

Provision is made for supplying oil to the burner in regulatable quantities from a source of supply not shown through a supply pipe 33 with which there is associated a conventional regulating valve 34. As shown, the bottom wall 22 of the burner is formed to provide a well or sump 35 into which the oil flows from the supply pipe 33.

To facilitate mounting the burner 17 within the casing 10, the latter is provided with a radially inwardly extending annular shoulder 36 between the upper and lower portions of the casing. The burner is mounted within the casing with the radially outwardly extending burner rib 28 engaging the radially inwardly extending casing rib 36, and is secured in that position by means of an adjustable screw element 37 threadedly mounted in the straps 12 and 13 and the free extremity of which engages the bottom of the burner. The straps 12 and 13 are secured to an inturned flange 38 at the lower extremity of the casing 10 by means of bolts 39.

As is clearly shown in the drawing, baffle means 26 in its entirety is located between the uppermost and lowermost primary air inlet openings 30. It is essential that it be arranged within the burner so that none of the horizontal sections A, B, C and D and none of the vertical walls E are positioned directly in front of an air inlet opening 30. Best results are obtained if one of the lower baffle sections C or D is positioned over the fuel sump 35. Section C is here shown as so positioned.

The operation of the apparatus herein shown and described is as follows:

The valve 34 is opened and oil flows into the burner. The oil is ignited by inserting a match or lighted taper through the door 18 and dropping it onto the bottom of the burner. Initially, and so long as oil is admitted to the burner in limited quantities only, combustion will occur in the lower part of the apparatus below baffle means 26. As the rate of flow of oil is increased the zone in which combustion is initiated rises within the apparatus until at the maximum flow of oil the lower limit of the zone of combustion will be localized adjacent the top of the burner in the region of the central opening in the top wall. The anti-explosion baffle prevents the lower limit of the zone of combustion from rising above that point in a well known manner, thereby eliminating the possibility of explosions. As is well known, it is an inherent characteristic of the present apparatus that the lower limit of the zone of combustion may be localized at substantially any desired point between the bottom of the burner and the top of the burner by proper adjustment of the regulating valve.

During the lower operating stages, when combustion is located in the lower part of the burner,

the baffle sections A, B, C and D prevent the formation of eddy currents to an extent sufficient to avoid interference with the normal process of combustion at those stages of operation. In this connection, it should be mentioned that eddy currents are prevented from flowing circumferentially between the baffle sections by the vertical walls E. By reason of the staggered arrangement of the baffle sections, the entire lower part of the burner is broken up into a series of more or less separate but communicating compartments or zones, thus precluding the formation of eddy currents of any consequence. By locating one of the lower baffle sections over the fuel sump 35, the initial combustion is protected from the disturbing influence of eddy currents.

From the foregoing, it will be apparent that the present invention provides an improved burner capable of stable, and therefore clean, combustion throughout its entire lower range (lower oil flows) of operation. By providing a large central passageway from the lower to the upper part of the burner and arranging the baffle means between the air apertures 30, the characteristic high fire operation of burners of this type is not adversely affected.

The scope of the invention is indicated in the appended claims.

We claim:

1. In a burner of the vaporizing pot type including a bottom wall, a tubular side wall provided with a plurality of vertically and circumferentially spaced apart air inlet apertures, and a fuel inlet opening formed in one of said walls adjacent the side of the burner and below said air inlet apertures, the improvement which comprises baffle means disposed within the burner comprising a plurality of arcuate sections the axial projections of which constitute a centrally apertured annulus, alternate sections being located in vertically spaced horizontal planes with the adjacent ends thereof lying in a substantially common radial plane, and vertical walls of a radial width equal to the radial extent of said baffle sections connecting the adjacent ends of adjacent baffle sections to each other.

2. A burner as defined in claim 1 wherein the baffle sections and vertical walls are located between the air inlet apertures whereby to avoid direct impingement of air thereagainst.

JOHN W. MILLER.
